Black and Decker Advertising Flyer, front side of page, Air Line Package—Air Filter+Air Regulator+Air Lubricator, middle of page.

[73] Assignee: Metal Work S.p.A., Concesio, Italy

Primary Examiner—James M. Gandy

[**] Term: 14 Years

Assistant Examiner—Lisa Lichtenstein

[21] Appl. No.: 20,316

Attorney, Agent, or Firm—Finnegan, Henderson, Farabow, Garrett & Dunner

[22] Filed: Feb. 27, 1987

CLAIM

[30] Foreign Application Priority Data

The ornamental design for combined filter, regulator, and lubricator for the flow of compressed air, as shown and described.

Sep. 19, 1986 [IT] Italy ..... 23148/86[U]

[52] U.S. Cl. D23/365

[58] Field of Search D23/355, 364, 365;
210/488

DESCRIPTION

[56] References Cited

FIG. 1 is a side elevation view of a combined filter, regulator, and lubricator for the flow of compressed air, showing our new design, the opposite side being a mirror image of that shown;

FIG. 2 is a top plan view thereof;

FIG. 3 is a bottom plan view thereof;

FIG. 4 is a right end elevation view thereof; and

FIG. 5 is a left end elevation view thereof.
